His Attorney

UNITED STATES PATENT OFFICE

2,245,201

RAILWAY SPRING HANGER

Ole K. Kjolseth, Erie, Pa., assignor to General
Electric Company, a corporation of New York

Application February 13, 1940, Serial No. 318,765

5 Claims. (Cl. 267—54)

My invention relates to improvements in railway vehicle spring hangers.

An object of my invention is to provide an improved railway spring hanger fabricated of welded elements.

Further objects and advantages of my invention will become apparent and my invention will be better understood from the following description referring to the accompanying drawing, and the features of novelty which characterize my invention will be pointed out with particularity in the claims annexed to and forming part of this specification.

In the drawing, Fig. 1 is a side elevational view of an embodiment of my improved spring hanger; Fig. 2 is an end view of the spring hanger shown in Fig. 1; Fig. 3 is a side elevational view of another embodiment of my improved spring hanger; Fig. 4 is an end view of the spring hanger shown in Fig. 3; Fig. 5 is a side elevational view of a further modification of my improved spring hanger; and Fig. 6 is an end view of the spring hanger shown in Fig. 5.

Referring to the drawing, I have shown in Figs. 1 and 2 a railway vehicle spring hanger which is fabricated by welding together elements formed of conventional structural material. By constructing a spring hanger in this manner, it is possible to provide hangers of various shapes and sizes according to the exact requirements of the vehicle suspension system without the labor and expense required for making cast units of this type. Furthermore, such a fabricated welded structure provides these spring hangers with the desired strength without the use of any special securing devices, such as bolts, screws, or removable pins which might be the cause of the loose connections between the parts of the hangers. As shown in these figures, a substantially cylindrical cross pin 10 formed of a section of steel rod is inserted in an aperture 11 formed in an end of a side bar or strap 12. In order to provide the usual stirrup type hanger, I provide a pair of these side bars 12 arranged one adjacent each end of the cross pin 10 and weld the cross pin to the side bars around the surface of the aperture 11, as indicated at 13. These side bars 12 are secured together intermediate the ends thereof by a cross web including a web plate 14 and flanges 15 and 16 welded on the longitudinal edges of the plate 14 and welded to the side bars 12. This cross web is secured to the side bars 12 at a point removed from the cross pin 10, so that the ends of a leaf spring or the end of an equalizer may be inserted between the cross pin and the cross web.

In order to provide a good bearing surface for the cross pin on the ends of the leaf springs or the equalizer, I provide a curved bearing element 17 of any suitable bearing material, which is welded at 18 to the cross pin 10. The ends of the side bars 12 opposite the aperture 11 away from the cross pin 10 are formed with openings 19 in order to provide for supporting a cross bar on which the end of an equalizer or a leaf spring may be mounted. This improved spring hanger provides a rigid and simplified construction without any relatively movable parts, and also reduces the cost of construction and maintenance thereof.

In Figs. 3 and 4, I have shown another embodiment of my invention wherein the vehicle spring hanger comprises a cross pin 20 to which a pair of side bars or straps 21 are welded. These side bars 21 are formed with apertures 22 adjacent one end thereof and are arranged with the cross pin 20 extending through the apertures 22 with one side bar adjacent each end of the cross pin. The side bar and the cross pin are securely connected together by welding, a shown at 23, on the inside and the outside of the side bars. These side bars are also connected together by a cross web 24 which is welded at the ends thereof to the side bars at a point spaced from the cross pin 20, so as to provide for the insertion of the end of a spring or an equalizer therebetween. In this construction, the cross web 24 is arranged adjacent the end of side bars 21 opposite to the apertures 22, and a hanger strap 25 is welded thereto adjacent the central portion thereof. The end 26 of the strap 25, opposite the end which is secured to the cross web 24, is enlarged to provide a support in the form of a spring seat for a coil spring. The bearing surface of the cross pin 20 is improved by securing thereto a curved bearing element 27 formed of any suitable bearing material by welding it to the under side of the cross pin 20.

In Figs. 5 and 6, I have shown a further modification of my invention providing a simplified vehicle spring hanger. In this construction, a cross pin 28 is formed of a piece of structural steel rod and is arranged to be supported on the end of a leaf spring or of an equalizer bar. The supporting surface of this cross pin is provided with a curved bearing element 29 of any suitable bearing material which is welded to the under side of the cross pin 28 to provide a better wearing surface. A pair of side bars or straps 30 is provided with an aperture adjacent one end of each bar arranged one over each end of the cross pin 28. These straps 30 are securely welded to the cross pin 28 on each side thereof, as shown at

31, and are formed with an opening 32 in the opposite end of the side bars to provide for supporting a cross bar which is adapted to engage the end of a leaf spring or an equalizer bar. This provides a very simple and rugged construction which is economical to manufacture and provides a unit without movable parts.

While I have illustrated and described particular embodiments of my invention, modifications thereof will occur to those skilled in the art. I 10 desire it to be understood, therefore, that my invention is not to be limited to the particular arrangements disclosed, and I intend in the appended claims to cover all modifications which do not depart from the spirit and scope of my 15 invention.

What I claim as new and desire to secure by Letters Patent of the United States is:

1. A railway vehicle spring hanger including a cross pin, and a pair of side bars each having an 20 aperture adjacent an end thereof fitted over said pin and welded thereto one adjacent each end of said pin, said bars being formed adjacent the other end thereof for providing a support.

2. A railway vehicle spring hanger including a 25 substantially cylindrical cross pin, a curved bearing element welded to said cross pin, a pair of side bars each having an aperture adjacent an end thereof fitted over said pin and welded thereto

adjacent an end of said pin, said bars being formed adjacent the other end thereof for providing a support.

3. A railway vehicle spring hanger including a cross pin, a pair of side bars welded adjacent an end thereof to said pin one adjacent each end of said pin, said bars being formed adjacent the other end thereof for providing a support, and a cross web extending between said side bars at a point removed from said cross pin and welded to said side bars.

4. A railway vehicle spring hanger including a cross pin, a pair of side bars each having an aperture adjacent an end thereof fitted over said pin and welded thereto one adjacent each end of said pin, said bars being formed adjacent the other end thereof for providing a support, and a cross web extending between said side bars at a point removed from said cross pin and welded to said side bars.

5. A railway vehicle spring hanger including a cross pin, a pair of side bars each having an aperture adjacent an end thereof fitted over said pin and welded thereto one adjacent each end of said pin, a cross web extending between said side bars at a point removed from said cross pin and welded to said side bars, and means secured to said cross web for providing a support.

OLE K. KJOLSETH.
